UNITED STATES PATENT OFFICE.

SARAH E. B. SHEPARD, OF LOWELL, MASSACHUSETTS.

ENSEMBLE UNDERGARMENT.

Application filed January 29, 1926. Serial No. 84,668.

This invention relates to women's apparel, more particularly to a step-in undergarment of the ensemble type, and has for its object to provide, in a manner as hereinafter set forth, a garment of the type referred to comprising combined waist, skirt and drawers portions and with the skirt portion provided with means for detachably connecting therewith hose-supporters for anchoring the ensemble, when worn, to the hose of the wearer to prevent the bodily shifting of the garment as an entirety when positioned upon the body of the wearer, and further to overcome any discomfort during the wearing of the ensemble.

A further object of the invention is to provide, in a manner as hereinafter set forth, a step-in undergarment of the ensemble type for overcoming the inconvenience to a wearer when independently arranging an underwaist, a skirt and a pair of drawers in position to be worn.

Further objects of the invention are to provide, in a manner as hereinafter set forth, an undergarment of the ensemble type which is comparatively simple in its construction and arrangement, strong, durable, thoroughly efficient in its use, and comparatively inexpensive to manufacture.

With the foregoing and other objects in view, the invention consists of the novel construction, combination and arrangement of parts, as hereinafter more specifically described and illustrated in the accompanying drawings wherein is shown an embodiment of the invention, but it is to be understood that changes, variations and modifications can be resorted to which fall within the scope of the claim hereunto appended.

In the drawings wherein like reference characters denote corresponding parts throughout the several views:—

Figure 1 is a perspective view of the garment.

Figure 2 is a like view of the garment turned inside out looking towards the front thereof.

Figure 3 is a fragmentary view in perspective of the garment turned inside out looking towards the back thereof.

Figure 4 is a fragmentary view in vertical section.

Figure 5 is a fragmentary view in vertical section upon an enlarged scale of the front portion of the garment.

Figure 6 is a view similar to Figure 5, of the rear portion of the garment.

Referring to the drawings in detail a step-in garment in accordance with this invention comprises a combined underwaist and skirt portion and a drawers portion surrounding the skirt and depending from the underwaist. The combined underwaist and skirt is formed from a one-piece body portion in the form of a continuous, non-split band. The underwaist part is indicated at 1, the skirt part at 2 and the drawers part at 3. A lining 4 is provided for the skirt part 2 and for the lower portion of the underwaist part 1.

The combined underwaist and skirt portion is formed of a ply or length of suitable fabric of the desired width and length preferably silk folded upon itself transversely and having the opposed edges thereof secured together by stitching 7. The lining 4 is also formed from material similar to that from which the combined underwaist and skirt is formed. The lining 4 is formed from a folded ply or piece of material of less width, but of the same length as the ply from which the combined underwaist and skirt portion is made. The opposed ends of the ply of material from which the lining is formed are secured together by the stitching 7, and also by the latter to the combined underwaist and skirt portion. The top of the lining 4 is secured to the underwaist part 1, at a point a substantial distance below the top of the latter by the stitching 8, and the bottom of the lining 4 is secured by the stitching 9 to the lower edge of the skirt part 2. The combined underwaist and skirt part is of greater height than the height of the lining 4.

The drawers part 3 incloses the skirt part 2, and is secured at its top to the combined underwaist and skirt portion at the point of emergence of the waist part 1 with the skirt part 2, by superposed rows of stitching 10, or in other words, the top of the drawers part 3 is secured to the combined underwaist and skirt or one-piece body portion, at a point below the transverse center of the latter and in proximity to its lower end. The drawers part 3 is of materially greater length than the skirt part 2 and depends a substantial distance below the latter. The drawers part 3 is of greater width than the waist part 1 and is formed of a ply or

piece of fabric of the same material as the waist and skirt parts. The ply from which the drawers part 3 is formed is bent upon itself and the bend 5 provided by the folds forms the bottom edge of the drawers part 3. After the ply has been folded it is cut away at the sides in a curvilinear manner and when the drawers part 3 is secured to the combined waist and skirt portion the said cut away portions at the sides of the drawers part 3 provide leg openings 11. The bend 5 provides a crotch. Coextensive with the edge of each opening, as well as being secured thereto and projecting outwardly therefrom is a ruffle 12. The ply or piece of fabric, with the ruffle attached to each side edge thereof, when folded and secured to the skirt part, provides a two fold body open at each side for a part of its length and with the free terminal portions of its folds inclosing and depending from the skirt part. The rows of stitching secure the side edges, at the free ends of the folds, in sidewise abutting relation and further secure the free ends of the folds to the skirt part and lining. The bend 5, between the folds of the ply or piece of fabric, is of less length than the width of the latter.

Secured to the outer face at the front of the skirt part 2 is a pair of reinforcing members 13 which have their lower edges flush with the bottom edge of the skirt part 2, and the latter at the front thereof is provided with a pair of button-holes 14 which extend through the members 13. The button-holes 14 provide means for connecting hose supporters 15 to the skirt, and each of the supporters 15 at its top is provided with a button 16 for passage through a button-hole 14 to secure the supporter to the skirt part 2. Secured to the outer face at the back of the skirt part 2 is a pair of spaced combined reinforcing and tab forming members 17, which depend below the bottom edge of the skirt part 2, and each has its depending portion formed with a button-hole 18, for the passage of a button 19 at the upper end of a hose supporter 20 arranged at the back of the skirt part 2. The members 17 are arranged a greater distance apart than the arrangement of the members 13 in spaced relation with respect to each other.

At the top of the skirt part 2, there is

secured thereto, at the front and back thereof, and on its inner face a loop forming member 21 for suspension purposes.

The top of the underwaist part 1 is formed with a hem 22 and secured to the latter and extending from the part 1 is a pair of shoulder straps 23.

The top of the garment acts as a brassière and the garment takes the place of a step-in, girdle, undervest and brassière and which may be termed a four in one garment, and is entirely free of hooks, eyes, elastics and bones.

It is thought that the many advantages of an ensemble undergarment, in accordance with this invention, can be readily understood, and although the preferred embodiment of the invention is as illustrated and described, yet it is to be understood that changes in the details of construction can be had which will fall within the scope of the invention as claimed.

What I claim is:—

An undergarment of the ensemble step-in type comprising a one-piece body portion in the form of a continuous, non-split band providing a combined underwaist and skirt part, a lining in the form of a continuous, non-split band for and of less height than the height of said body portion, means for securing the upper end of the lining to said body portion a substantial distance below the top of the latter, means for securing the lower end of the lining to the lower end of the body portion, a two-fold body open at each side for a portion of its length and with the bend between the folds of less length than the width of these latter thereby providing a drawers part, the free ends of the folds of said two-fold body positioned against the outer face of said body portion at a point below its transverse center and in proximity to its lower end, rows of stitching for securing the free ends of the folds in side-wise abutting relation and further for securing the free ends of the folds to said body portion and lining, and said bend between the folds forming a crotch and positioned at the lower end of said two-fold body.

In testimony whereof, I affix my signature hereto.

SARAH E. B. SHEPARD.
